WELT HOOK

Hans J. Straussberger, Brooklyn, N. Y., assignor to Alfred Hofmann, Inc., West New York, N. J.

Original application June 29, 1939, Serial No. 281,767. Divided and this application April 17, 1940, Serial No. 330,027

17 Claims.

(Cl. 66—96)

The present invention relates to welt hooks and, more particularly, to welt hooks especially intended for use in forming welts in straight knitting machines, according to the method disclosed in my co-pending application, Serial Number 281,767, filed June 29, 1939, of which this application is a division.

The invention primarily aims to provide welt hooks having a novel construction whereby certain improvements in the mode of operation for turning welts on straight knitting machines may be had.

A particular object of the invention resides in the provision of welt hooks having spring beards and latches cooperatively associated therewith, and provided with needle beard receiving grooves relatively disposed with respect to said hook beards and latches whereby to assure positive engagement and co-function of elements for the manipulating of the loops in setting up courses to effect the formation of welts on straight knitting machines.

The invention is particularly characterized by the provision of welt hooks in a welt bar, each hook having at one end a relatively long beard whereby the latter may springably move towards and away from the body of the shank, and provided with a pivotal latch disposed to swing towards and away from the hook beard, said latch being positively limited in its swinging movements so that it may be caught and displaced by a loop or strand of yarn being moved relatively along the length of the welt hook.

Other important objects and advantages of the invention will be in part obvious and in part pointed out hereinafter.

In order that the invention and its mode of operation may be readily understood by those skilled in the art, I have, in the accompanying drawings and in the detailed description based thereupon, set out a possible embodiment of the invention.

In these drawings:

Figure 1 is a top plan of a portion of a welt bar provided with a bank of welt hooks constructed in accordance with this invention;

Figure 2 is an enlarged section taken on line 2—2 of Figure 1;

Figure 3 is a top plan of the preferred latch type of welt hook constructed in accordance with this invention;

Figure 4 is a side elevation of the same;

Figure 5 is an enlarged section taken on line 5—5 of Figure 3;

Figure 6 is an enlarged section taken on line 6—6 of Figure 4;

Figure 7 is a perspective on a considerably enlarged scale of the preferred form of latch embodied in the welt hook;

Figure 8 to 16 inclusive are somewhat diagram-

matic representations illustrating the hook and associated machine parts during the various stages of their functions to effect the formation of the welts.

Referring more particularly to the drawings, wherein like characters of reference will designate corresponding parts throughout, there is shown in Figures 1 and 2 a welt bar 20 comprising complementary bar sections 22 and 24, one bar section 22 having a longitudinal recess 26, and the other bar section 24 having a series of spaced transversal grooves and holes, such as represented at 28 and 30 respectively. The bar sections 22 and 24 are rigidly held together by means of bolts 32, or like fastening elements, that securely clamp therebetween a bank of welt hooks 34.

Each welt hook 34 preferably has the construction shown in Figures 3, 4, and 5, and essentially comprises a shank 36, a hook end 38, and a butt end 40, a portion of the shank and the butt end being respectively adapted to fit into a groove 28 and a hole 30 of the bar section 24 (Figure 2).

That portion of the shank 36 which projects outwardly of the bar sections 22 and 24 is formed at its normal front side with a needle beard receiving groove 42. The hook end 38 of the welt hook shank 36 is preferably flexible, constituting a beard 44 with which a latch 46 is adapted for cooperative action. For that purpose, the hook shank 36 is shown at its normal rear side as formed with a pair of ears 48 between which is pivotally mounted the latch 46, the tip 50 of which has a slight recess or groove 52 engageable with the tip 54 of the hook beard 44, as more clearly shown in Figure 5. A pin 56 may constitute the pivot for the latch 36.

From the foregoing description, it will be understood that the latch 46 may be swung about its pivot pin 56 easily, without opening or closing springs, but under sufficient friction that it tends to remain in its set position to which it may be swung, although it will operate as well even if free and loose. In one position, the latch 46 may be swung downwardly to engage and guard the tip 54 of the hook beard 44 by the groove 52 at the tip 50 of the latch, but the latch is preferably of a length that it will only slightly overlap the tip 54 of the hook beard 44 whereby a yarn loop may pass down and off from the latch onto the beard.

It will also be appreciated that the latch 46 in either of its extreme positions to which it may be swung is adapted to be caught and displaced by a loop or strand of yarn being moved relatively along the length of the welt hook. At the hook beard engaging position of the latch, this result may follow from the yielding depression of the flexible hook beard 44 by the tension of the yarn loop due to which the loop sliding up

along the beard is caused to depress said hook beard and thus enter and engage the shank 36 beneath the latch 46 when required, so that continued upward sliding of the loop or yarn operates to swing said latch around from its lowered or hook beard engaging position to its raised or hook beard disengaging position.

In practice, the hook beard 44 and the latch 46 preferably are cooperatively shaped so that the tip 50 of the latch normally projects slightly outwardly of the hook beard tip 54, thus assisting to assure that the relatively raising yarn loop will enter between the hook beard and latch, even if the pressure of the yarn is deficient. In its raised position, the latch 46 stands out from the hook shank 36 to a sufficient extent to insure that a yarn loop sliding relatively downwardly will engage between the shank and latch, and with continued descent, will cause the latch to swing around and down to its hook beard guarding or engaging position.

The body of the shank 36 between the pivot ears 48 is shaped to constitute two stop surfaces 58 and 60, one on each side of the pivot pin 56. The lower stop surface on that side of the pivot pin 56 nearest to the tip 54 of the hook beard 44 limits the depression of the latch 46 towards the shank 36 so that said latch cannot follow the hook beard 44 inwardly when the yarn is intended to pass from the hook beard beneath the latch. The other stop surface 60 prevents the raised latch 46 from lying flatly against the shank 36 and so insures its protruding to admit the yarn between said latch and shank. The latch 46, therefore, needs no springs nor any shifting or reversing means, other than the relative movements of the yarn itself as the welt hook 34 is shifted downwardly and upwardly.

The operation of the welt hooks 34 will be more clearly understood upon reference to Figures 8 to 16 inclusive, showing the various successive stages or positions of said welt hooks for receiving sinker loops of the initial course knitted by the needles of the knitting machine, and returning said loops to the needles.

In these figures, there has been shown only those parts of a full-fashioned knitting machine which are operatively associated with the welt hooks for cooperation in the formation of welts.

The knitting needles are indicated at N, and are provided with spring beards B at the rear side of their normal top ends.

The ordinary notch sinkers S are mounted to slide, as usual, in a sinker head H, one portion P of the sinker head H constituting a press edge for closing the needle beards at certain times, as customary in the art.

In Figure 9 is indicated an ordinary yarn carrier C operable to lay yarn on the sinkers S behind the needles N and, in accordance with this invention, behind the welt hooks 34 in the manner to be described hereinafter. The knockover bits K are of conventional construction and united in a knock-over frame F.

The first general part of the operation is the hook-up, the various successive stages of which are represented in Figures 8 to 13 inclusive. In the first part of the hook-up operation, the conventional narrowing motions are taken advantage of, the machine being initially set to put the needles N, sinkers S, and knockover bits K through the narrowing motions, in cooperation with which the welt hooks 34 are manipulated. The arrows appearing in the various diagrams are intended to show approximately the direc-

tion of movement which the respective instruments have just passed in bringing them to the illustrated positions.

In the position illustrated in Figure 8, the welt hooks 34 have advanced, risen, tilted upright, hurdled over the needles, and descended behind the latter, with the hook beards 44 facing rearwardly and the hook tips 54 lower than the sinkers S.

In the position illustrated in Figure 9, the hooks 34 have been bodily shifted frontwardly. The narrowing motion has caused the sinkers S to retract and the needles N to rise substantially. The frontward shift of the welt hooks, therefore, causes the groove 42 of each welt hook to receive and enclose its corresponding needle N and to close the beard B thereof. These movements bring the parts in position to receive the first course of yarn laid upon the sinker tips behind the beards 44 of the welt hooks 34. The loops of the first course are preferably formed in the usual manner by the regular sinking and dividing movements.

The initial course having been laid, the parts reach the position shown in Figure 10, where the yarn Y is seen as passing around the sinker throats and to the rear of the welt hook beards 44. A loop is thus caused to pass around the hook beard 44 below the latch 46. It will be noted that in the position shown in said Figure 10, the frontward thrust of the sinkers S applies substantial tension to the yarn Y so that the yarn deflects forwardly the beard 44 of each welt hook 34, thus creating a thread passage between the welt hook beard 44 and latch 46 such as to insure the passage of the loop beneath the latch, with the subsequent descent of the welt hook. Without this action and tension, the relatively rising yarn would accidentally pass from the welt hook beards onto the latch and thus obstruct the performance of the subsequent actions to be described.

As above stated, Figure 10 shows the loops as positioned on the hook beards 44 below the latches 46. Therefore, the yarn lays in front of the sinker throats and behind the welt hook beards and associated needles.

In the position shown in Figure 11, the welt hooks 34 have lowered somewhat more than sufficiently to cause the yarn to rise and pass from the hook beards 44 and beneath the latches 46. This shift, as shown, is carried so far that the yarn rides up on the latches 46, opening them but not passing beyond them. The needles N are shown as partaking of the lowering movement of the hooks. The stage shown is only momentary, since the hooks 34 immediately rise again while the needles N continue to descend.

This brings the operation to the position shown in Figure 12. The hook rise has caused the yarn Y to enter between the hook shank 36 and beard 44. The descent of the needles N has brought their beards B opposite the press edge portion P. The needles N and hooks 34 have moved rearwardly until the needle beards B are pressed closed. The hooks 34, therefore, carry the loops free of the needles, each hook being in the plane of its empty needle.

The hooking-up operation is completed as follows:

In the position shown in Figure 13, the needles N have moved forwardly and downwardly while the sinkers S have completed their retraction to discharge the yarn Y; the welt hooks 34 have shifted frontwardly carrying the yarn Y beyond

the sinkers S; and the hooks thereupon tilt over through positions shown in dotted lines in Figure 13, towards their substantially flatwise position in which they operate to draw off the fabric being knitted.

As the welt fabric knitting progresses, the welt hooks 34 advance, rise, and tilt upwardly, as shown in dotted lines in Figure 14, preparatory to the transfer of the initial sinker loops back onto the needles N.

As indicated in the full line in Figure 14, the sinkers S have shifted frontwardly, and both ends of the fabric lie between the sinkers S and knock-over bits K. The needles N have engaged the initial sinker loops on the welt hooks 34. At the same time, the hooks 34 have descended to a point where the initial sinker loops have relatively passed up along the hooks above the beards 44 and beyond the latches 46, lifting the latter and riding onto the shank 36 of said hooks.

In the position shown in Figure 15, the welt hooks 34 have ascended again. The initial sinker loops, during this upward retraction, ride down over the hook shanks 36, throwing down the latches 46 and sliding over the same. The hooks, however, are rising and are pulled bodily through the loops which pass from the latches 46 to the beards 44 and then off the hooks 34 onto the needles N.

As shown in Figures 16, as the needles N rise, the initial sinker loops are forced by the sinkers S down onto the needle shanks where they remain in superposed relationship with the loops of the last course of the welt fabric to be locked on the next succeeding course of the stocking leg fabric.

The positions shown in dotted lines in Figure 16 illustrate the return movement of the welt hooks 34 to their initial inoperative position where they remain until the next welt forming operation is to take place.

Manifestly, it will be understood that the construction herein shown and described is capable of certain modifications without departing from the gist of the invention. Therefore, any modifications coming within the scope of the subjoined claims are to be considered within the spirit of the invention.

What I claim is:

1. A welt hook comprising a shank, a spring beard formed continuously with the shank at one end thereof, a latch mounted on one side of the shank at a point adjacent to the tip of said beard, and a needle receiving groove formed on the opposite side of the shank.

2. A welt hook comprising a shank terminating at one end with a relatively long beard capable of springably moving towards and away from the body of the shank; a latch pivotally mounted on the beard side of the shank to normally engage the tip of the beard when sprung away from the body of the shank; and stop means disposed to prevent the latch from following the movement of the beard when sprung towards the body of the shank.

3. A welt hook comprising a shank terminating at one end with a relatively long beard capable of springably moving towards and away from the body of the shank; a latch pivotally mounted on the beard side of the shank to normally engage the tip of the beard when sprung away from the body of the shank; stop means disposed to prevent the latch from following the movement of the beard when sprung towards the body of the shank; and a needle groove formed

on that side of the shank opposite to the beard side thereof.

4. A welt hook comprising a shank terminating at one end with a relatively long beard capable of springably moving towards and away from the body of the shank; a latch pivotally mounted on the beard side of the shank to normally engage the tip of the beard when sprung away from the body of the shank; and stop means on the shank engageable with the latch to prevent the same from following the movement of the beard when sprung towards the body of the shank.

5. A welt hook comprising a shank terminating at one end with a relatively long beard capable of springably moving towards and away from the body of the shank; a latch pivotally mounted on the beard side of the shank to normally engage the tip of the beard when sprung away from the body of the shank; stop means on the shank engageable with the latch to prevent the same from following the movement of the beard when sprung towards the body of the shank.

10 15 20 25 30 35 40 45 50 55 60 65 70 75

6. A welt hook comprising a shank terminating at one end with a spring beard movable towards and away from the body of the shank; a latch pivotally mounted on the beard side of the shank to swing to opening and closing positions, said latch, when swung towards closing position, engaging the tip of the beard when swung away from the body of the shank; stop means disposed to prevent the latch when swung to closing position from following the movement of the beard towards the body of the shank; and stop means disposed to prevent the latch when swung to opening position from engaging the body of the shank.

7. A welt hook comprising a shank terminating at one end with a spring beard movable towards and away from the body of the shank; a latch pivotally mounted on the beard side of the shank to swing to opening and closing positions, said latch, when swung towards closing position, engaging the tip of the beard when swung away from the body of the shank; stop means disposed to prevent the latch when swung to closing position from following the movement of the beard towards the body of the shank; stop means disposed to prevent the latch when swung to opening position from engaging the body of the shank.

8. A welt hook comprising a shank terminating at one end with a spring beard movable towards and away from the body of the shank; a latch pivotally mounted on the beard side of the shank to swing to opening and closing positions, said latch, when swung towards closing position, engaging the tip of the beard when swung away from the body of the shank; stop means on the shank engageable with the latch when swung to closing position to prevent the same from following the movement of the beard towards the body of the shank; and stop means on the shank engageable with the latch when swung to opening position to prevent its engagement with the body of the shank.

9. A welt hook comprising a shank terminating at one end with a spring beard movable towards and away from the body of the shank; a latch pivotally mounted on the beard side of the shank to swing to opening and closing positions, said latch, when swung towards closing position, en-

gaging the tip of the beard when swung away from the body of the shank; stop means on the shank engageable with the latch when swung to closing position to prevent the same from following the movement of the beard towards the body of the shank; stop means on the shank engageable with the latch when swung to opening position to prevent its engagement with the body of the shank; and a needle groove formed on that side of the shank opposite to the beard side thereof.

10. In a united bank of welt hooks adapted to cooperate with the needles and other knitting instruments of a flat knitting machine: a welt hook member having an elongated shank mounted for longitudinal up and down movements in relation to a yarn in engagement therewith and constructed with a loop holding flexible beard at the lower end of its shank; a beard guarding latch pivoted to the shank above the hook to swing on an arc longitudinally of the shank and beard for placement in an upper position and in a lower position, said latch being so formed that when in its upper position the yarn sliding along the shank, and when in its lower position the yarn sliding along the beard, may enter under the latch whereby all necessary latch reversing movements for loop hooking and discharging purposes may be effected by the up and down movements of the welt hook member in relation to the yarn.

11. In a united bank of welt hooks adapted to cooperate with the needles and other knitting instruments of a flat knitting machine: a welt hook member having an elongated shank mounted for longitudinal up and down movements in relation to a yarn in engagement therewith and constructed with a loop holding flexible beard at the lower end of its shank; a beard guarding latch pivoted to the shank above the hook to swing on an arc longitudinally of the shank and beard for placement in an upper position and in a lower position, said latch being so formed that when in its upper position, the yarn sliding along the shank, and when in its lower position, the yarn sliding along the beard, may enter under the latch whereby all necessary latch reversing movements for loop hooking and discharging purposes may be effected by the up and down movements of the welt hook member in relation to the yarn; and said hook member having positive stops limiting the swing positions of the latches so that its tip will protrude and form a yarn entering recess beneath the tip.

12. In a united bank of welt hooks adapted to cooperate with the needles and other knitting instruments of a flat knitting machine: a welt hook member having an elongated shank mounted for longitudinal up and down movements in relation to a yarn in engagement therewith and constructed with a loop holding flexible beard at the lower end of its shank; a beard guarding latch pivoted to the shank above the hook to swing on an arc longitudinally of the shank and beard for placement in an upper position and in a lower position, said latch being so formed that when in its upper position, the yarn sliding along the shank, and when in its lower position, the yarn sliding along the beard, may enter under the latch whereby all necessary latch reversing movements for loop hooking and dis-

charging purposes may be effected by the up and down movements of the welt hook member in relation to the yarn; said hook member having positive stops limiting the swing positions of the latch so that its tip will protrude and form a yarn entering recess beneath the tip; and said shank having a needle beard receiving groove formed on the side thereof opposite the latch.

13. A welt hook comprising a shank having on one side a spring beard and a latch therefor, and on the opposite side a needle receiving and covering groove.

14. In a united bank of welt hooks adapted to cooperate with the needles and other knitting instruments of a flat knitting machine: a welt hook member having an elongated shank mounted for movements in relation to a yarn in engagement therewith and constructed with a loop holding beard; a beard guarding latch pivoted to the shank to swing on an arc longitudinal of the shank and beard for placement in a beard opening position and a beard closing position, said latch being so formed that when in its beard opening position, the yarn sliding along the shank, and when in its beard closing position, the yarn sliding along the beard, may enter under the latch whereby all necessary latch reversing movements for loop hooking and discharging purposes may be effected by the movements of the welt hook member in relation to the yarn.

15. A welt hook comprising a shank, a spring beard formed at one end of the shank and extended in a plane paralleling a portion on one side of the shank, a latch mounted on said side of the shank and disposed to engage the terminating end portion of the beard but leaving the major portion of said beard exposed, whereby a yarn sliding on the latter may pass between the latch and said portion of the beard covered thereby, and a needle receiving and covering groove formed on, and located to extend throughout, a portion on the other side of the shank opposite to said portion on the first mentioned side of the shank.

16. A welt hook comprising a shank having a hook end with its tip extended to terminate at a point along the intermediate portion on one side of said shank, a latch pivoted at one end to said side of the shank and disposed to cover said tip of the hook end for closing the latter, the free end of said latch extending beyond said tip but leaving the major portion of said beard exposed, whereby a yarn sliding on the latter may enter beneath said latch, and a needle receiving and covering groove formed on, and located to extend throughout, a portion on the other side of the shank opposite to said portion on the first mentioned side of the shank.

17. A welt hook comprising a shank provided with a hook end and a needle receiving and covering groove, said hook end extending over a portion on one side of said shank and having a length sufficient to form an outer surface capable of being engaged by a yarn for the sinking of a loop thereover, and said groove being located to extend throughout a portion on the other side of the shank opposite to said portion on the first mentioned side of the shank and over which said hook end extends.
